Primary Examiner—Ian Simmons*Assistant Examiner*—Wan Laymon(74) *Attorney, Agent, or Firm*—Perkins Coie LLP(57) **CLAIM**

The ornamental design for the camera support, as shown and described.

DESCRIPTION

FIG. 1 is an isometric view of a camera support showing my new design.

FIG. 2 is a front elevation view of the camera support.

FIG. 3 is a back elevation view of the camera support.

FIG. 4 is a left side elevation view of the camera support.

FIG. 5 is a right side elevation view of the camera support.

FIG. 6 is a top plan view of the camera support; and,

FIG. 7 is a bottom plan view of the camera support.

The broken line showing of portions of the camera support is for the purpose of illustrating the camera support and forms no part of the claimed design.
